OUTBOARD MOTOR

Warren C. Conover, Waukegan, Ill., assignor, by
mesne assignments, to Outboard, Marine &
Manufacturing Company, Wilmington, Del., a
corporation of Delaware

Application March 11, 1936, Serial No. 68,238

3 Claims. (Cl. 115—18)

This invention relates to improvements in outboard motor.

It is the object of the invention to provide a practical form of outboard motor in which the power head has been so lowered that its center of gravity is approximately at or below the level of the transom. I propose in this manner to improve the stability of the craft to which the motor is attached; to accomplish a very substantial reduction in noise, and to remove all dirty or greasy parts, and all electrical connections, to a position where they will not accidentally be contacted by the operator.

In order to make my improved invention practicable for modern outboard motor conditions and modern boats, it is a further object of the present invention to provide an extended arm between the sub-crank case swivel bearing and the bracket pintle upon which the motor tilts for steering, thus permitting the said swivel bearing to be located well below the top of the boat without interfering with the tilting function.

It is a further and very important object of the invention to enclose, at least to a substantial degree, the entire power head in a sheath or casing which protects all of the parts from contact with the water. The boats with which outboard motors are used now commonly have low transoms, and in order that the power head may be lowered with respect to the transom, it is necessary that it be brought into close proximity to the normal water line where waves might readily splash it but for the protection thus provided. The mere location of the power head behind the transom is an important factor contributing to the reduction of noise and the elimination of dirt, and the enclosing casing makes an important additional contribution to these objectives and also gives a smooth and more or less streamlined enclosure which enhances the appearance of the device.

In the drawings:

Figure 1 is a view partly in elevation and partly in section, of an outboard motor embodying the principles of this invention.

Figure 1a is a fragmentary detail view showing a modified construction in which the sub-crank case swivel bearing is reduced in length and is supplemented by a second swivel bearing above the crank case.

Figure 2 is a front and part sectional view of the motor shown in Figure 1.

Figure 3 is a top view of the motor shown in Figure 1, the bracket being omitted.

Figure 4 is a view mostly in section of a modification.

Figure 5 is a sectional view at the top of the casing, of the motor shown in Figure 4.

Figure 6 is a front view of the motor unit shown in Figure 4, the bracket being omitted.

Figure 7 is a section taken on the line 7—7 of Figure 4.

Figure 8 is a section taken on the line 8—8 of Figure 4.

Figure 9 is a plan view on an enlarged scale, of the motor shown in Figure 5.

Figure 10 is a fragmentary detail in section showing the tiller connections to the dirigible drive shaft housing on the inside of the motor casing.

Figure 11 is a detail view in section showing a modified construction employing a single water passage and anti-friction elements in the swivel bearing.

Figure 12 is a detail view in plan of a portion of the transom bracket and the supporting part of the casing of the device shown in Figure 4.

Figure 13 is a detail view in section taken on the line 13—13 of Figure 4.

Like parts are identified by the same reference characters throughout the several views.

Referring now more particularly to the drawings, this invention may be illustrated as applied to an outboard motor having a lower driving unit 10 as shown in Figs. 1 and 2, with a short drive shaft casing 11 connecting it to an engine power head 12. At the top of the power head and connected to the engine crank shaft is a fly-wheel 13 of a magneto controlled by a handle 14 and having a rope starter plate 15 at the upper end thereof. At the rear and partially nesting the fly-wheel 13 is a fuel tank 16, and an enclosing casing 17 extends entirely over the power head, over the fuel tank 16, and around and over the magneto fly-wheel 13, leaving only the rope starter plate exposed through an opening in the upper side of the casing. The casing is secured to the power head in any suitable manner and a portion thereof is engaged between flanges 18 and 19. Exhaust pipe 20 connects the engine cylinder 21 with the rear of the lower unit 10 which conducts the exhaust gases to an opening 21 below an anti-cavitation plate 22 at the rear of the propeller 23.

This structure as a unit is mounted in a split sleeve swivel bearing 25 at the lower end of an arm 26 which has an offset intermediate portion 27 and an upper end 28 mounted in a transverse

55 55

pivot 28 in a bracket clamp 38 attachable to a boat transom 36 by a fastening screw 32.

The bracket clamp has two side portions with the arm 26 mounted upon the pivot 28 between them. Inclined slots 33 in the side portions receive an adjustable thrust bolt 34 engaged by the front edge of the arm 26. Thus the engine and the power head are low with respect to the tilting pivot 28, thereby providing a low center of gravity, making the boat more safe and stable, and less likely to overturn, and reducing the overall length of the motor from top to bottom.

For steering, the motor is rotatable in the split sleeve 25, and a handle 35 may be secured directly to the casing 17 at one side of the fly-wheel as shown more clearly in Fig. 3.

The device shown in Fig. 1a of the drawings is identical with that shown in Figs. 1 and 2 excepting that the arm 26 of the bracket is provided with an extension 280 carrying a supplemental swivel bearing in the form of a split sleeve 280 applied to a boss above the crank case. Because of the provision of this supplemental swivel bearing it is unnecessary to employ so long a bearing at 251 below the crank case, and this effects a further reduction in the center of gravity of the device.

In the form shown by the remaining figures of the drawings, an engine 50 is enclosed in a casing 51 which has forward extensions 52 for pivotally mounting the entire structure to tilt about a horizontal pintle 53 carried by a bracket 54 secured by a screw clamp 55 to the transom 56 of a boat. Formed unitarily with the casing is a hollow casing extension 57 and a muffler extension 58. In order that the casing structure may be locked against tilting during the reversal, I may either provide automatically interlocking parts as disclosed in Patent No. 1,467,641, or I may provide for manual locking of the parts by threading a nut 530 upon the pintle 53 and providing said nut with a handle 531 as shown in Figs. 9 and 11, whereby the clamping pressure of the nut will slightly distort the sides of the bracket against the casing to frictionally resist tilting movement.

Turnable in the casing 51 is a lower unit 60 which has a sleeve 61 fitting within the swivel bearing 57 and adapted to receive the extended engine drive shaft leading to the propeller 63. A gear 64 secured at the top of the casing 61 provides means for retaining the washers 65 and 66 in place to form a bearing.

Water passages 67 and 68 terminate at an arch 69 over the path of the propeller blades and these passages extend upwardly to ports 70 and 71 respectively. The port 70 communicates with a passage 73 extending upwardly in the swivel bearing 57 and thence around the outside of the casing in a passage 74 as shown more clearly in Figures 4 and 8. At the top of the muffler extension 58 is a partition 75 below a casing wall 76 with a wall 77 dividing this flat chamber into two passageways 78 and 79, the former communicating with the water passage 72 and the latter communicating with the passage 74.

The engine 50 has a cylinder casing 80 and a cylinder cap 81 therefor provided with a water jacket and a pipe connection 82 extends through the casing wall 76 and into communication with the passageway 78 at the bottom of the water jacket, and a pipe connection 83 extends from the top of the water jacket through the cylinder head 81 and downwardly to the passageway 79 at the other side of the partition 77. Thus when

the engine is in operation a supply of cooled water is impelled by the propeller 63 upwardly through the passage 67, port 70, passage 72, passageway 78, pipe fitting 82 through the engine cooling system, outwardly through the pipe connection 83, passageway 79, passages 74, 73, port 71, and passage 68 from the lower casing 66 in front of the propeller 63.

As the lower driving unit is rotatable in the relatively fixed casing 51 for the purpose of steering, the passages 72 and 73 as shown more clearly in Fig. 7, extend partially around the casing extension 51 less than one hundred eighty degrees so that the ports 70 and 71 will remain in communication with them respectively during the ordinary steering movements of the lower driving unit 60. However, in case it is desired to reverse the position of the lower driving unit, for propelling the boat rearwardly, the ports 70 and 71 will be reversed with respect to their ordinary passages 72 and 73 respectively and the direction of flow of the cooling water will therefore be reversed in the passages and water jacket above the ports 70 and 71. However, as the passages and water jacket above these ports 70 and 71 are all full of water at the time reversal takes place the pressure and suction exerted by the propeller is sufficient to reverse the flow of cooling water through the water jacket and the connected passages in the casing 51.

At the rear of the casing 51 is an opening closed by a door 85 mounted on a hinge 86 at one side thereof and substantially conforming to the outline of the casing to provide a smooth and substantially stream line surface, the door being normally held in closed position by a spring 87 connected at one end to a rib 88 of the door and at the other end to a suitable fixed portion of the engine. The spark plugs 89 and a valve 90 in the gasoline line connection 83 are freely accessible through this opening when the door 85 is maintained in open position, and the closure of the door protects these parts and closes the casing against the admission of water.

At one side of the engine cylinders is a muffler 92 which has an opening registering with the exhaust openings of the cylinder and has a passage 93 extending downwardly at the side of the casing 51 and registering with an opening 94 in the wall of the muffler 58 below its partition 75 so that the exhaust is discharged into the muffler extension 58 and escapes through a discharge passage 58' at the bottom thereof below an ant cavitation plate extending from the outer surfaces of the lower driving unit 60 and the lower rear end of the muffler extension 58.

In order to rotate the lower unit in the casing 57, for steering, an idler gear 96 is mounted in the casing which meshes with the gear 64 and with a gear 97 at the opposite side thereof at one side of and beyond a flywheel magneto 98 and a starting plate 100 at the top of the motor. A steering handle 102 is secured to the upper end of the shaft 98 and at the outer end is pivoted a hand lever 103 which has an extension 104 co- operating with a stop 105 on the handle 102 so that it will engage the stop both in the horizontal and vertical positions of the handle. This steering handle is therefore freely rotatable in either direction and the lower driving unit is correspondingly rotated as the gear 97 is preferably of the same diameter as the gear 64 with which the idler 96 meshes.

In the structure thus described the casing may house merely the engine as shown, with an ex-

tension 106 about the flywheel magneto and with a separate and outer fuel tank 107 as shown, or these parts may be included in the same casing as shown in Figs. 1, 2 and 3. The outline of the 5 lower unit also closely conforms to the adjacent surface of the muffler extension 58 so that when in normal position they are substantially parallel and adjacent each other.

To provide a freely rotatable connection between the supporting casing and the lower unit which is rotatable for steering, roller bearings 110 may be inserted between crank case extension portions 111 and 112 corresponding to the casing members 57 and 60 respectively. In this form a 10 single water passage 113 is shown having an outer annular groove 114 between the bearings 110 which continuously registers with a passage 115 in the casing 111. After passing through the water jacket of the engine the cooling water 15 is discharged directly into the muffler extension as shown in Fig. 4 or it is discharged overboard from the engine. Between the casings is a cork seal 116 engaging an inclined surface 117 above the annular groove 114 and pressed in engagement therewith by a spring 118 which prevents any of the water or air from passing upwardly between the casings. A projection 119 at the bottom of the annular groove 114 forms a substantially tight connection with the outer casing 20 25 30 35 40 45 50 55 111 so that any small water leakage between the casings will serve to lubricate the lower bearings 110.

Many of the details of outboard motor structure are omitted from the drawings and description because they have no special reference to the present invention and would only obscure and confuse the invention in this case.

With both of these constructions the outboard motors are mounted to tilt about a vertical axis substantially at the top of the engine, the portions which are pivoted for steering and the pivotal mounting thereof being well below the engine itself and substantially in the shaft casing portion between the power head and the lower driving unit. The arm which extends from the tilting axis to the swivel bearing may be separate as suggested in Fig. 1 and Fig. 1a, or it may include or be a part of the engine or engine case as suggested in Fig. 4 and Fig. 11. This provides a wider bearing portion and also reduces the length of the shaft casing between these parts to make them shorter than the constructions heretofore employed. The resulting structure is less in height and the engine being mounted lower with respect to the upper edge of the boat transom provides a safer outboard motor structure for use

in connection with small boats. By providing a substantial closure for the engine and operating parts it is possible to mount the motor lower at the back of a boat and still to experience no detrimental effects from the splash of the water short-circuiting the spark plugs or other electrical connections. 5

I claim:

1. In an outboard motor structure, the combination with a relatively stationary power head 10 and a lower unit rotatable for the reversal of its direction of propulsion, of a bearing including relatively stationary water cooling ducts extending from said bearing to and from said power head, and complementary ducts connected with 15 said lower unit and extending from and to submersible inlet and outlet ports therein, and means for circulating water through said ducts, the ducts of the lower unit being adapted to register with different stationary ducts in said bearing according to the direction of propulsion of said lower unit. 20

2. In an outboard motor structure, the combination of a relatively stationary power head, a bearing therebeneath provided with oppositely 25 ported walls and stationary ducts leading from the ports in said walls to and from said power head, means rotatable in said bearing and provided with a submersible lower unit having inlet and outlet ports, ducts leading from the inlet and 30 outlet port to a position in said means registerable with said first mentioned ducts, and a propeller carried by said lower unit and positioned in association with at least one of said ports to circulate water through said ducts, the ducts 35 leading from the lower unit being arranged to register with different ports in said bearing according to the position of said lower unit in its rotative adjustment respecting said bearing. 40

3. In an outboard motor structure, the combination with a casing and a power head enclosed therein, of a swivel bearing below said casing, a dirigible shaft housing and lower unit journaled in said bearing and extending into said casing, a vertical tiller shaft rotatable in said casing and 45 provided therewithin with driving connections to said shaft housing, a crank on said tiller shaft exposed above said casing, and a handle on said crank pivoted for movement from the plane of said crank to an upright position thereon, said 50 tiller shaft carrying said crank at a level such that it may be rotated for the reverse of the direction of propulsion of the lower unit without interference with said casing. 55

WARREN C. CONOVER.
